FIG. 1.

Harry A. Koenig.
Robert M. Barr. Attorney

UNITED STATES PATENT OFFICE.

HARRY A. KOENIG, OF PHILADELPHIA, PENNSYLVANIA.

GAS-IRON.

1,383,216.

Specification of Letters Patent. Patented June 28, 1921.

Application filed April 8, 1919. Serial No. 288,486.

To all whom it may concern:

Be it known that I, HARRY A. KOENIG, a citizen of the United States, and a resident of Philadelphia, in the county of Philadelphia and State of Pennsylvania, have invented a certain new and useful Improvement in Gas-Irons, of which the following is a specification.

Some of the objects of the present invention are to provide a gas iron wherein the ironing surface is maintained uniformly heated; to provide means to prevent back firing and choking of the flame due to currents of air produced when the iron is in use; to provide means to maintain an even predetermined circulation of the heated products; to provide means for carrying off the waste products without permitting air to enter the iron body by way of the exhaust vents; and to provide other improvements as will hereinafter appear.

In the accompanying drawings Figure 1 represents a side elevation of a gas iron embodying one form of the present invention; Fig. 2 represents a top plan of the same; Fig. 3 represents a transverse section on line 3—3 of Fig. 1; Fig. 4 represents a top plan of the hollow body part of the iron; and Fig. 5 represents a plan of the device for forming air passages and shielding the handle portion from the discharged products of combustion.

Referring to the drawings one form of the present invention is shown wherein a body 10 is provided which preferably consists of a solid weighted base 11 and a hollow top casing 12 arranged to be removably secured to the base 11 thereby forming in assembled condition a chamber 13. The base 11 in the preferred form is substantially elliptical providing oppositely pointed ends 14, and having a flat finished bottom face 15 for the usual ironing purpose.

For removably securing the casing 12 to the base 11 a plurality of machine screws 16 are employed which are adapted to pass through openings 17 respectively in the casing 12 and have screw-threaded engagement with the base 11, so that in operation the two parts of the body are fixedly secured together.

In order to heat the body 10 and particularly the base 11 and the ironing face 15 thereof, the casing 12 is cut away or recessed at the rear end to receive a burner 18 of any suitable form but preferably of the Bunsen

type and the arrangement is such that when the burner 18 is in operative position, and held by a set screw 20 or like fastening means, the flame will be directed downwardly upon the base 11 and forwardly to the toe of the body 10. Gas is admitted to the burner 18 by way of the hollow stem 21 and mixing nipple 22, which latter is arranged to receive the usual gas supply tube. 65

For the purpose of concentrating the flame upon the base 11 the burner 18 is arranged to direct the flame into a main combustion chamber 23 formed by a deflector 24 which is removably secured to the casing 12. In 70 the present instance this deflector 24 is provided with side flanges 25 arranged to seat on the base 11 and having openings 26 at suitable intervals along the edges to permit the products of combustion to pass laterally 75 into the chamber 13.

In order to promote combustion effectively the casing 11 is provided with a plurality of air inlets or passages 27 arranged along the bottom circumferential edge of the casing 11 80 to form communication between the chamber 13 and the exterior of the body 10. These inlets 27 introduce air in close proximity to the discharge opening or openings in the deflector 24 so that complete combustion 85 takes place and the desired blue heating flame is maintained.

As a means for securing a uniform circulation of the heated products within the body 10, and also preventing choking or smothering of the flame when the iron is in use, the inner wall 30 of the casing 11 curves inwardly and upwardly from the floor of the base 11 at each side in a relatively long, uniform sweeping curve with its highest portion substantially coincident with the line of intersection between the casing 12 and the vertical longitudinal axial plane of the body 10. At opposite sides of this plane the casing 12 is provided respectively with two 90 series of relatively large vents 31, arranged substantially in alignment longitudinally of the casing 12 while between these series of vents are a plurality of smaller outlets 32 so located as to release products which pass to 95 the highest portion of the chamber 13. 100

To further promote combustion and produce an artificial draft a plate 33 is provided consisting of a pair of laterally disposed, elongated concave wings 34 which are 110 connected together by a strip 35 interposed between them and arranged to be fixed in

place upon the body 10 by screws 36 or other fastening devices. Preferably these screws 36 also serve to hold the handle 37 by which the iron is manipulated in use.

5 These wings 34 in operative position have their respective concave portions juxtaposed with respect to the outer top surface of the casing 12 but spaced therefrom a suitable distance to form channels 40 extending 10 longitudinally of the iron body 10. This spacing is effected by the provision of upstanding lugs 41 so that in assembled condition there is a free air space between the plate 33 and the casing top, which space 15 takes the form of two parallel channels disposed respectively above the two series of vents. As the outlets 32 discharge beneath the strip 35 it is evident that all the discharged products of combustion enter the 20 space beneath the plate 33 and are then carried longitudinally of the body and dissipated.

In the operation of the iron the flame from the burner 18 is projected within the 25 chamber 23 where it is fed by air entering by way of the passages 27 and 25 to support combustion while the products pass outwardly through the openings 25 and pass upwardly, being directed by the curved 30 walls to the main vents 31 and supplemental outlets 32. As the iron is reciprocated in use currents of air pass first in one direction and then in the other through the channels 40 and perform the double function of drawing out the products from the casing 12 and 35 keeping the plate 33 cool. The function of maintaining a circulation of the products is an important one and it is desirable to definitely proportion the size and numbers of 40 the vents 31 and 32 with respect to the area of the channels 40 because too many or too large vents result in the too rapid withdrawal of the products which directly affects the efficiency of the iron, 45 while too few vents chokes the combustion. By the present invention the flame is not subjected to air currents tending to force it laterally through the air inlets and thus burn articles being ironed, and this is true 50 irrespective of the direction of movement of the iron. It will further be evident that the outlet vents for the waste products are arranged to all discharge the products transversely to the path of the moving currents 55 of air and in consequence they are carried away instead of being forced back into the combustion chamber. Since in the preferred form the body comprises two separable parts it is desirable to provide means for 60 lighting the burner without opening the casing and to that end one of the air inlets adjacent to the rear of the body is enlarged sufficiently to permit a match or the like to be inserted for starting the burner. This 65 opening is indicated at 42. While but one

form of the invention has been shown by way of example, it will be understood that the same is not limited to the exact construction shown as various modifications may be made without departing from the invention. 70

It will now be apparent that the present invention provides a free uniform flame which is unaffected by currents of air in the operation of the iron, and wherein the air acts in a predetermined manner to assist and 75 promote the circulation of the products so that any tendency to choke the flame is overcome.

Having now described my invention what I claim is:—

1. In a gas iron, the combination of a body provided with a series of air inlets in close proximity to the bottom of said body and two series of vents in the top, a burner, and means arranged to form two longitudinally disposed channels across the top of said body in vertical alinement with said series of vents respectively.

2. In a gas iron, the combination of a body provided with a plurality of air inlets, 90 and a plurality of discharge openings in the top of said body, a burner, and a plate secured to said body and spaced therefrom, said plate forming a plurality of longitudinally disposed channels above said discharge openings, said discharge openings being proportioned in area with respect to the area of said channels.

3. In a gas iron, the combination of a body provided with a plurality of air inlets, 100 and a plurality of discharge openings in the top of said body, a burner, and means to produce a suction at said openings in either direction of movement of said body, whereby the products of combustion circulate continuously and back pressure is prevented 105 when the iron is in operation.

4. In a gas iron, the combination of a body provided with a plurality of air inlets, two series of vents in the top of said body, 110 and outlets between said two series of vents, a burner, and a plate having two concave wings forming channels respectively in alinement with said two series of vents, and a strip in alinement with said outlets, whereby a current of air is produced in either direction of movement of said body to promote circulation of the products within said body.

5. In a gas iron, the combination of a 120 body provided with a plurality of air inlets, two series of vents in the top of said body, and outlets between said two series of vents, a burner, and a plate having two concave wings forming channels respectively in 125 alinement with said two series of vents and a strip in alinement with said outlets, said vents and outlets being proportioned in a predetermined ratio to the area of the space between said plate and said body.

6. In a gas iron, a hollow body provided with a plurality of air inlets in close proximity to the bottom of said body and two series of vents in the top of said body, a deflector forming a combustion chamber and provided with openings juxtaposed with respect to said inlets, a burner arranged to project a flame within said combustion chamber, and a plate secured in spaced relation upon said body and forming two longitudinal channels disposed respectively above said two series of vents, the dimensions of said channels being proportioned to the combined areas of said vents, whereby a free flow of products of combustion is maintained in either direction of movement of said iron.

7. In a gas iron, a hollow body forming a heat chamber, a deflector in said chamber forming a combustion chamber, said deflector having lateral openings arranged to discharge into said heat chamber, said body having sides provided with outlets to admit air against the outwardly discharged products from said openings, said body also having a top provided with a plurality of discharge openings arranged in a predetermined manner, means forming a plurality of air channels axially of said body and above said top discharge openings, and a burner arranged to deliver fuel to said combustion chamber.

HARRY A. KOENIG.
